(57) CLAIM

The ornamental design for a vehicle, as shown and described.

DESCRIPTION

FIG. 1 is a front view of a first embodiment of the vehicle of the present invention;

FIG. 2 is a rear view thereof;

FIG. 3 is a right side view thereof;

FIG. 4 is a left side view thereof;

FIG. 5 is a front left side perspective view thereof;

FIG. 6 is a rear left side view thereof;

FIG. 7 is a rear right side perspective view thereof;

FIG. 8 is a front right side perspective view of a second embodiment of the vehicle;

FIG. 9 is a rear right side perspective view of FIG. 8;

FIG. 10 is a front view of FIG. 8; and,

FIG. 11 is a rear view of FIG. 8.

The environment surrounding the vehicle in the figures does not form part of the claimed design. The license plate letters and numbers do not form part of the claimed design. The stands beneath the vehicle in FIGS. 1-7 do not form part of the claimed design.
